BALNEOTHERAPY APPARATUS

Robert T. Melsheimer, Hollywood, Calif.

Application October 14, 1950, Serial No. 190,177

4 Claims. (Cl. 128—369)

1

This invention relates to balneotherapy apparatus and deals more particularly with apparatus for creating a constant supply of myriads of bubbles to produce certain beneficial physiological effects on the body of a person immersed in a bath.

The therapeutic value of air bubbles in hydrotherapy is now becoming more fully recognized and has been found beneficial in the treatment of many diseases and abnormal conditions of the body. Such therapy has been employed for its beneficial, gentle and soothing effects on insomniacs, expectant mothers, convalescents and enfeebled persons, and for the beneficial results obtained in the treatment of hypertension, circulatory disturbances, rheumatic and arthritic conditions, metabolic diseases, skin diseases, and many other abnormal nervous conditions. Stimulation of the skin, capillaries, and nerve ends has been found to also beneficially affect the vascular and vegetative nervous systems of persons in normally good health, as well as those suffering from disorders such as above mentioned.

In order to be wholly effective, an air bubble bath should create two primary effects. One, a direct effect on the skin to create improvement in the peripheral circulation and a change in the ionic content of the skin and an increase in its esophylactic functions and, two, indirect or reflective effects resulting in changes in the autonomic nervous system and its functions.

The efficacy of the foregoing is a direct function of the number of air bubbles created, the larger the number and, in the main, the smaller their size, the greater the beneficial effects. Accordingly, an important object of the present invention is to provide apparatus of the character indicated, that is highly efficient to continuously produce myriads of relatively small bubbles to effect a substantially complete covering thereby of the skin of the patient.

Another object of the invention is to provide air-bubble-forming apparatus that may be used in the home with salutary effects equal to that obtained when administered by professionals and with complete safety.

Another object of the invention is to provide apparatus that includes a novel grid-like element adapted to be positioned on the bottom of a bath tub, the same being provided with novel means for producing, from a supply of compressed air, a large amount of extremely small air bubbles that permeate the bath.

The invention also has for its objects to provide such means that are positive in operation, convenient in use, easily installed in a working position and easily disconnected therefrom, economical of manufacture, relatively simple, and of general superiority and serviceability.

The invention also comprises novel details of

2

construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views:

Fig. 1 is a plan view of apparatus according to the present invention and shown in operative position.

Fig. 2 is an enlarged fragmentary plan view of the bubble-generating grid of said apparatus.

Fig. 3 is a fragmentary longitudinal sectional view of said grid and a support therefor.

Fig. 4 is a cross-sectional view as taken on line 4—4 of Fig. 3.

A typical bath tub 5 is shown in Fig. 1, the same being used to hold a quantity of water at a desired temperature. In the use of the present means, thermal stimulation is increased as the temperature of the water is increased, as can be understood. Chemical stimulation may be created by the admixture in the water of certain salts, sulphur, oil of ether, organic extractions, etc. While the present invention makes no claim to the creation of the beneficial effects of thermal and chemical stimulation, the present improved means considerably increases the pharmacodynamic effect of additive chemicals, whether dissolved or in suspension, through efficient and continuous creation of myriads of extremely small air bubbles and the accompanying increase in skin stimulation.

The present apparatus comprises, generally, a grid 6, means 7 for supplying a continuous supply of compressed air to said grid, and a support 8 for the grid, both the grid and support being positioned on the bottom of tub 5 while the means 7 is located outside the tub.

The grid 6 comprises a series of parallel tubes 9 that are connected at one end by a manifold header 10 and, at the opposite end, by a bar 11. The drawing shows four tubes 9 although the number may vary as desired. Tubes 9 and header 10 are preferably of rectangular cross-section substantially as shown. Where each tube 9 connects to the header there is provided an externally threaded tubular nipple 12 on said header, the same having connection with a plug 13 in the adjacent end of the respective tubes 9. Each plug 13 is provided with a passage 14 in communicating extension of the passages in nipples 12.

In the lower portion of each tube 9 is positioned a channel member 15 that extends longitudinally from within a lower recess 16 in each plug to a point short of the opposite end of tube 9. The end of the channel that resides in recess 16 is provided with a notch 17 that serves to con-

nect passage 14 and the longitudinal passage 18 that is formed between channel 15 and the bottom wall 19 of tube 9. It will be clear that compressed air in header 10 will readily pass into passage 18 of each tube 9 substantially without resistance.

Flexible tube 20, which conducts compressed air to header 10, is shown connected to a central point of said header. In order that the outer tubes 9 receive substantially the same amount of air from the header that is received by the two intermediate tubes 9, the passages in nipples 12 that connect to said intermediate tubes are proportionally smaller than the passages in the nipples that connect to the outer tubes. Should tube 20 be connected to one end of the header, the nipple passages are proportionally increased as their remoteness from the air connection increases to obtain the mentioned uniformity of air flow to all of tubes 9.

Between top wall 21 of each tube 9 and transverse wall 22 of channel 15 therein there is formed a longitudinal chamber 23 in which is placed a continuous strip 24 of felted or matted material, the same being drawn into said chamber from one end of the tube and tightly fitted therein so as to be under some compression. Thus, assurance that strip 24 completely fills chamber 23 is had. It will be clear that said strip embodies a multiplicity of pores or interstices that are quite uniformly distributed throughout the length of the strip.

A set of openings 25 are provided in channel wall 22 and another set of openings 26 are provided in tube walls 21, said sets of openings being preferably elongated substantially as shown.

A plug 27, affixed by screws 28, to bar 11 extends into the end of each tube 9 and is held in place by screws 29. A felt filler piece 30 is interposed between the inner end of each plug 27 and the adjacent end of both channel 15 and strip 24.

While compressed air freely passes into and fills passage 18, the strip 24, despite its numerous pores, will act to retard air flow therethrough, thus insuring as much air flow from the far ends of tubes 9 as from the ends adjacent header 10. Only such air as will pass through strip 24 will pass through openings 26 and the same will be so attenuated that extremely fine air bubbles will be released into the water of the bath and quite uniformly through the extent of the grid.

The means 7 comprises a box 31 which, essentially houses an air pump 32 and an electric motor 33 to drive said pump. Comparable means may be provided to supply certain beneficial gases, such as carbon dioxide or pure oxygen, instead of compressed air or to supplement the same. Thus, means 7 may comprise a tank of precompressed air or gas or mixtures thereof, as desired.

Support 8 is preferably formed as a platform which is separably interfitted with the elements of the grid. As shown, said support comprises a set of parallel planks 34 that extend in the spaces between tubes 9 of the grid. Said planks are connected by transverse cleats 35 and are spaced therefrom by spacer blocks 36. Said blocks are of such height that, with the grid resting on cleats 35, planks 34 are elevated with respect to the grid and serve to space the body of the user from the grid. Thus, said grid is not subjected to the weight of the user, the same being borne by the support, and the air-passing openings 26

are at no time obstructed by the user's body for free ingress of air bubbles into the bath water. Support 8 is preferably fabricated of wood members.

While the invention that has been illustrated and described is now regarded as the preferred embodiment, the construction is, of course, subject to modifications without departing from the spirit and scope of the invention. It is, therefore, not desired to restrict the invention to the particular form of construction illustrated and described, but to cover all modifications that may fall within the scope of the appended claims.

Having thus described the invention, what is claimed and described to be secured by Letters Patent is:

1. A gas-bubble-discharging unit comprising a set of elongated and parallel tubes each having discharge openings, a header connecting said tubes at one end and supplying gas thereto, a longitudinal partition having openings therein and positioned between that portion of each tube having the discharge openings and the opposite portion of the tube, said partition dividing the tube into substantially coextensive longitudinal chambers, and a strip of felt material in the chamber of each tube that is defined and compressed between that portion of the tube having the discharge openings and the mentioned partition.

2. The gas-bubble-discharging unit according to claim 1: each of said tubes having a flattened rectangular cross-section in which the width dimension is greater than the height dimension, the mentioned discharge openings being provided in the upper flat wall of each tube.

3. In a grid of the character described, a plurality of similar tubes each having an open end to receive gas under pressure and an opposite closed end, each tube being of rectangular cross-section to have upper, lower and side walls, the upper wall having discharge openings therein, a perforated partition in each tube spanning between the side walls thereof and dividing the same into longitudinal chambers, the lower of said chambers constituting a gas-conducting passage, and a filler of compressed porous material in the other chamber and filling the same.

4. A gas-bubble-discharging unit comprising a set of elongated and parallel tubes each having discharge openings, a header connecting said tubes at one end and supplying gas thereto, each tube having a passage therealong and in direct communication with the header, a strip of felt material in each tube between its passage and discharge openings, and a longitudinal perforated channel member disposed within each tube and, together with a wall of the latter, defining the mentioned passage, said channel member also confining the strip of felt material against an opposite wall of the tube.
